FIGURE 1 is a perspective view of a table or similar article, showing my new design;

FIGURE 2 is a top plan view thereof;

FIGURE 3 is a front elevational view thereof; and

FIGURE 4 is a side elevational view thereof.

The dominant features of my design reside in the portions shown in full lines on the drawing and is characterized by the combination on the table disclosed of a rectangular top having spaced L-shaped tray members attached to the undersurface thereof, a plurality of such members being positioned along opposing sides of the top and protruding outwardly therefrom, all as best shown in FIGURES 2 and 4.

I claim:

The ornamental design for a table or similar article, as shown and described.
